UNITED STATES PATENT OFFICE.

JOSEPH O. COTTRELL, OF FANWOOD, NEW JERSEY.

ELECTRIC-WIRE PROTECTOR.

SPECIFICATION forming part of Letters Patent No. 278,886, dated June 5, 1883.

Application filed January 19, 1883. (No model.)

To all whom it may concern:

Be it known that I, JOSEPH O. COTTRELL, of Fanwood, Union county, in the State of New Jersey, have invented certain new and useful 5 Improvements in Electric-Wire Protectors, of which the following is a specification.

A form of protector has been proposed, and to some extent used, in which strips of board or other suitable material of proper thickness 10 are grooved on one face and applied by nails or other fastenings, with the grooved side against the wall, inclosing the wires in the grooves. The operation involves difficulties which the present invention is intended to 15 overcome. I employ two boards or analogous pieces of material, one lying upon the other against the wall, and form the grooves, not on the inner face of either of the pieces, but on the outer face of the piece which lies next to 20 the wall. This piece may be fastened to the wall in advance of the application of the wires. Then the wires are laid in their several grooves and temporarily held by any convenient means. Then the second strip is applied over 25 the first strip, with its wires, and being suitably fastened the whole is complete. In what I esteem the most complete form of the invention the outer or covering strip is narrower than the innermost, and is recessed a little into the 30 outer face of the inner board or other piece of material, and a tight joint is made between the outer and the innermost board, particularly at the top. The effect of the device is to protect the wires from mechanical disturbance, 35 and to a large extent from the access of moisture under all conditions. It prevents the wires from being injured, and also prevents the electricity in the wires from injuring the building or its occupants.

40 The following is a description of what I consider the best means of carrying out the invention.

The following drawings form a part of this specification.

45 Figure 1 is a front view of a considerable length of my wire-protector complete. Figs. 2, 3, 4, and 5 represent parts detached. Fig. 2 is a cross-section of the main part. Fig. 3 is a front view of a portion thereof. Fig. 4 is 50 a cross-section of the covering-board. Fig. 5 is a front view of a portion thereof. Fig. 6 is a cross-section representing the parts combined

and secured by proper fastenings to each other and to the wall. Fig. 7 is a front view corresponding to Fig. 6. Fig. 8 shows my device 55 for holding the wires in their respective grooves before the covering-piece is applied. This also shows a modification of the form of the edges. Fig. 9 represents one of the temporary fastening-pegs detached.

60 Similar letters of reference indicate corresponding parts in all the figures.

A is the wall of the building.

B is the innermost board, secured by screws or other fastenings, B', to the wall A. It is 65 formed with grooves, as b' b² b³, receiving the wires m, and the whole face immediately adjacent to these grooves is sunk slightly, as indicated by b. The edges of this sunk portion are peculiarly beveled, as shown. The upper 70 edge is beveled under. The lower edge is produced in a plane nearly parallel, but not quite parallel, thereto. The bevel on the lower edge is greater than that on the upper, as indicated by the dotted lines in Fig. 4. In preparing 75 the lumber the board B may be first treated in one or more machines to produce the broad and shallow depression b, extending nearly across the whole face, taking care to give the bevels to its edges, as described. Then by one 80 or more subsequent operations the several grooves b' b² b³ are formed in the bottom of the shallow groove b.

D is the covering-board. It is plane on the back, and is of a width on the back just equal 85 to that of the broad shallow groove b. It is secured by screws or other fastenings, C. In applying the parts together the fastenings C at the lower edge, being set up tightly, serve, by the greater inclination of the lower edge 90 than of the upper, to force the covering-board upward and to produce a close and water-tight joint at the upper edge. There may be additional fastenings C at or near the upper edge; but I propose to dispense with them in ordinary cases and depend upon the locking due 95 to the form of the parts at the upper edge. It is important to make the breadth of the covering-board D exactly equal to the width of the broad shallow groove b. In applying it 100 the upper and lower edges fit tightly against the corresponding surfaces at the edges of the grooves b. A further provision for the exclusion of all moisture accidentally received from

above, as by a leakage of water from some sourcee trickling down the wall, is by the introduction of a thin strip, d , of rubber, leather, or analogous yielding material. This is compressed when the fastenings C are tightened, and forms a water-tight joint between the parts B and D .

E is a strip of rubber or analogous water-proof elastic material, fitted in a saw-kerf in the main board B and allowed to project a little. When the covering-board D is applied and properly pressed home it forms a tight joint along both lines by compressing the rubber E . The lowermost rubber E is important in preventing the access of moisture in that direction, by capillary attraction or otherwise, when the protector is used on a perpendicular wall. It is obviously important when the device is used in the horizontal position and water is allowed by any chance to seek access in that direction. The wires m are secured temporarily in their respective grooves, before the application of the covering-board D , by means of small pegs G , of hard wood, analogous to shoe-pegs, but pointed at each end. These pegs G are made of a length a little greater than the width of the several grooves $b' b^2$, &c. As fast as each groove $b' b^2$, &c., receives its wire or wires the pegs G are inserted by suitable pliers and twisted around, so that the points cut into the sides of the groove and serve as reliable anchors to hold the wire. They serve to keep the wires in their several grooves independent of and additional to the covering-board D . It is important that the pegs G be of non-conducting material. I find wood admirably suited for the purpose, and by using hard wood for the pegs G and a softer wood for the board B there is little difficulty in engaging them in the manner indicated. Whenever a wire is to be removed or another added in any groove the several pegs G may be removed and replaced by seizing each in succession with suitable pliers and giving them a partial turning motion.

Modifications may be made in the forms and proportions. I have shown the several grooves as containing one wire m each. There may be a number of wires m , properly insulated from each other by a covering of gutta-percha or other suitable material. In some cases the device may be used with one or more wires in one groove and the other grooves empty.

My protector possesses the advantage over any others known to me that the wires may be examined at any time by removing or partially removing the outer board without disturbing the wires at all. It is also vastly easier to put up with the wires correctly placed, because the inner board can be first set in position, either finally or temporarily held, and

the wires placed in their proper grooves while the latter are in their final position. The covering-board is applied easily without disturbing the wires.

Parts of the invention may be used without the whole. The invention may be used in various positions. I can fasten it in a horizontal position on the floor or the ceiling. It is very frequently required in the latter position in practice.

The rubber d may be omitted and the rubber E depended on to make a sufficient defense against the access of moisture.

The locking by means of the bevels may be omitted, and the covering-board may enter by square edges, or both may be beveled flaring.

The face of the covering-board may be plane, as shown, or it may be variously molded or otherwise ornamented. For some reasons it may be preferable to swell the front, making the center of considerably greater thickness than the edges.

Instead of putting the strips of rubber E in the back board, B , they may be put in the front board, D , and form an equally tight joint by their protruding edges being pressed against the back board, B .

I claim as my invention—

1. The main board B , having grooves on its front, as $b' b^2$, held by fastenings B' , and the covering-board D , held by separate fastenings C , combined and adapted to serve relatively to each other and to the wires m as herein specified.

2. The covering-board D , beveled substantially as shown, in combination with the fastenings C and with the board B , having the broad shallow recess or groove b and narrow grooves $b' b^2$, and with the wires m , arranged in such groove, substantially as herein specified.

3. The soft strip or packing d , in combination with the boards B and D and fastenings C , as herein specified, the board B being formed with an undercut bevel at the upper edge and with an open or reverse bevel of a different obliquity at the lower edge, as set forth.

4. The soft strips or packings E , in combination with the grooved board B , wires m , covering-board D , and fastenings C , as herein specified.

5. The double-pointed pegs G , arranged, as shown, in the grooves $b' b^2$, in combination with the wires m , boards B and D , and fastenings C , as herein specified.

In testimony whereof I have hereunto set my hand, at New York city, N. Y., this 30th day of January, 1883, in the presence of two subscribing witnesses.

JOSEPH O. COTTRELL.
